J. W. LOCKERY

INDIVIDUAL TOOTHBRUSH STERILIZER AND HOLDER

Filed July 6, 1923

Patented Nov. 17, 1925.

1,562,348

UNITED STATES PATENT OFFICE.

JOHN W. LOCKERY, OF SCRANTON, PENNSYLVANIA.

INDIVIDUAL TOOTHBRUSH STERILIZER AND HOLDER.

Application filed July 6, 1923. Serial No. 649,899.

To all whom it may concern:

Be it known that I, JOHN W. LOCKERY, a citizen of the United States, residing at Scranton, in the county of Lackawanna and 5 State of Pennsylvania, have invented new and useful Improvements in Individual Toothbrush Sterilizers and Holders, of which the following is a specification.

The object of my said invention is the 10 provision of an individual tooth brush holder and sterilizer characterized by simplicity and cheapness of construction, the capacity to hermetically seal the brush that it contains, the adaptability to be quickly and 15 easily cleaned, and the facility with which a brush may be reached and sterilized and removed for use and the facility with which the brush may be replaced to drain and be sealed.

20 My invention also contemplates the making of the individual tooth brush holders and sterilizers of glass, porcelain or other vitreous material so as to promote the sanitary character of the devices and at the 25 same time render it feasible to make the devices in different colors of marked contrast so that different members of a family may have no difficulty whatever in identifying the holder and sterilizer that contains 30 his or her individual tooth brush.

To the attainment of the foregoing, the invention consists in the improvement as hereinafter described and definitely claimed.

In the accompanying drawings forming 35 part of this specification:—

Figure 1 is a side elevation showing a tooth brush holder and sterilizer constituting one embodiment of my invention.

Figure 2 is a vertical section of the same 40 taken in the plane indicated by the line 2—2 of Figure 1.

Figure 3 is a horizontal section of the same taken in the plane indicated by the line 3—3 of Figure 2 looking downwardly.

45 Figure 4 is a side elevation of a modified tooth brush holder and sterilizer.

Figure 5 is a vertical cross-section of another modification.

Figure 6 is a horizontal section of the

same taken in the plane indicated by the 50 line 6—6 of Figure 5, looking downwardly.

Similar numerals designate corresponding parts in Figures 1 to 3 to which reference will first be made.

The body 1 of my novel tooth brush holder and sterilizer is tubular in form, open at its upper end, and provided at its lower end with a heavy base 2 so that when it is desired to stand the body on a table or other support there will be little liability of the 60 body turning over. Primarily the body is designed to be hung on a wall support, and to said end the body is provided at 3 with an integral apertured lug adapted to be placed over the upstanding portion of a 65 bracket 4 such as shown in Figure 1. The said body 1 is of glass or other appropriate vitreous material, and the forward portion of its upright wall is of less height than the rear portion of said wall, as designated by 70 5 in Figure 2 so that when the cover 6 is removed from the body 1, the handle 7 of a tooth brush in the holder and sterilizer may be readily grasped for the removal of said brush from the holder and sterilizer as well 75 as for the convenient manipulation of the brush in the holder and sterilizer as will be hereinafter set forth in detail. The cover 6 is provided with a knob 8, preferably 80 knurled as illustrated, and it will further be noted that the cover is characterized by pendent annular flanges 9 and 10, spaced apart to receive between them the upper 85 end of the body 1 and also to seat between them a gasket 11 which is adapted to be superimposed on the upper end of the body 1 with a view to contributing to the hermetic closure of the body 1 when the tooth brush 7 is therein contained. At its underside the cover 6 is chambered as indicated 90 by 12 to receive the upper end of the handle of the tooth brush after the manner illustrated in Figure 2. I would also have it understood at this point that a ground joint is provided between the body 1 and 95 the cover 6, either by grinding one surface of the body 1 or by grinding one inner surface of one of the flanges 9 and 10, this to

assure the closure being air tight when the cover 6 is superimposed on the body 1. In the center of the bottom of the body 1 is a stud 13, and superimposed on the said bottom, about the said stud, is an expansion spring 14 which is adapted to rest in a body 15 of antiseptic solution and is also designed to yieldingly support a tooth brush supporting platform 16, the said platform having a central pendent portion 17 disposed in the upper convolutions of the spring and being also provided with spaced and bifurcated arms 18, Figure 3, so as to permit of the free passage of the solution that drips from the tooth brush bristles back into the body of solution contained in the lower portion of the body 1.

In the practical use of the embodiment illustrated, the tooth brush is held in the holder and sterilizer after the manner clearly shown in Figure 2, so that any excess solution that may be in the bristles of the brush can freely drip back into the body of solution. When it is desired to use the brush it is simply necessary for the user to remove the cover 6, and grasp the handle of the brush and then move the brush downwardly against the action of the spring 14 until some or all of the bristles of the brush are immersed in the body of antiseptic solution 15, whereupon the brush is removed from the body and is used in conventional manner, and then replaced in the body 1. Manifestly the comparatively low height of the upper end of the front portion of the body 1 will contribute materially to the facility with which the brush handle may be grasped and the brush may be manipulated in the manner described. It will also be noted here that when the brush is replaced in the body 1 and the said body 1 is closed through the medium of the cover 6, the brush will be completely isolated from the dust and air of the apartment in which the brush holder and sterilizer is disposed, and at the same time the brush will be yieldingly maintained by the spring above the body of antiseptic solution so as to thoroughly drain the antiseptic solution from the bristles back into the body of solution. It will further be noted that when it is desired to clean the holder and sterilizer, the same can be expeditiously and easily accomplished after the body 1 is removed from the bracket 4.

In the modification of my invention shown in Figure 4, the body 1^a is designed to receive antiseptic solution as shown together with a float 20 of glass or other appropriate material, the float being designed to be forced down to or near the bottom of the tubular body when the brush is pushed downwardly in the body, and the float being also designed upon removal of pressure from the brush to rise and support the

brush in raised position and with its handle end in position relative to the upper end of the body to permit of said handle end being conveniently grasped. It will also be noted that the float will serve when force is removed from the brush to support the brush above the solution so as to permit solution to drain from the bristles back into the body of solution. The float in practice will be made to closely fit the inside of the tubular body, though there will be sufficient clearance to permit the float to freely move up and down. Both ends of the float are rounded, and when desired the float can be removed for cleansing purposes by simply inverting the tube.

It will also be noticed that the upper end of the forward portion of the body 1^a is cut away as indicated by 5^a for the purpose before described with reference to the embodiment in Figures 1 to 3, and that the cover 6, in Figure 4, is exteriorly similar to the cover 6, of Figures 1 and 2.

In the modification of my invention shown in Figures 5 and 6, the body 1^x is partitioned to provide two compartments 1^b and 1^c, the compartment 1^b being designed to contain antiseptic solution 15^a, and the compartment 1^c being equipped at a slight distance above its bottom with a stationary foraminous rest 18^a. The body 1^a is flat at its rear side and rounded at its front side, and has its corners rounded so as to facilitate the thorough cleansing of the device.

In the use of the embodiment shown in Figures 5 and 6, the brush 7 is permitted to drain in the compartment 1^c, and the brush head is dipped into the body of solution 15^a precedent to use of the brush, and then after use of the brush, the brush is returned to the compartment 1^c, and the cover 6^a which as shown is formed with a concavity above the partition to allow fumes, vapor and the like from the antiseptic solution to pass above the partition and to the compartment 1^c so that it will come in contact with the brush therein as will be readily apparent upon viewing Figure 5 of the drawings. This action taking place after the cover has been replaced, which will also result in the brush being preserved in a hermetically sealed casing, and the bristles will be permitted to drain antiseptic solution into the lower portion of the compartment 1^c so that the drainings will also keep the brush in a sanitary condition.

Having described my invention, what I claim and desire to secure by Letters Patent, is:

An individual tooth brush holder and sterilizer comprising a body partitioned to provide two side by side compartments, one of said compartments being adapted to receive a predetermined quantity of antiseptic solution, a stationary foraminous rest

bridging the walls of the other compartment and arranged adjacent the lower end thereof to support a tooth brush to drain therein, a cover for said body and being formed with a concavity overlying the partition whereby fumes from the antiseptic solution in the solution compartment will pass above the partition into the other compartment.

ment and come in contact with the brush therein, parallel spaced flanges depending from the cover and engaging the inner and outer sides of the wall of the body and said wall and flanges cooperating to form a hermetically seal therebetween.

In testimony whereof I affix my signature.
JOHN W. LOCKERY.
